US0D1008525S

(12) **United States Design Patent** (10) **Patent No.:** **US D1,008,525 S**
(45) **Date of Patent:** **** Dec. 19, 2023**

(54) **LAMP**

(71) Applicant: **Dongguan Zhongtuo Intelligent Technology Co., Limited**, Guangdong (CN)

(72) Inventor: **Zhibin Yang**, Guangdong (CN)

(73) Assignee: **Dongguan Zhongtuo Intelligent Technology Co., Limited**, Guangdong (CN)

(**) Term: **15 Years**

(21) Appl. No.: **29/829,964**

(22) Filed: **Mar. 9, 2022**

(30) **Foreign Application Priority Data**

Jan. 15, 2022 (CN) 202230026781.7

(51) **LOC (14) Cl.** **26-05**

(52) **U.S. Cl.**

USPC **D26/88**

(58) **Field of Classification Search**

(57) **CLAIM**

The ornamental design for a lamp, as shown and described.

DESCRIPTION

FIG. 1 is a front, left and bottom perspective view of a lamp, showing my design.

FIG. 2 is a rear, right and top perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof; and,

FIG. 9 is an enlarged view showing a portion of the lamp labeled 9 from FIG. 2.

The broken lines in the drawings depict portions of the lamp that form no part of the claimed design. In addition, the dot-dash broken lines illustrate in the drawings illustrate an enlarged portion of the design.

1 Claim, 9 Drawing Sheets
